Application January 26, 1952, Serial No. 268,452

4 Claims. (Cl. 219—45)

1

This invention relates to a fixture for holding infrared lamps for use particularly in chicken or pig brooding wherein the lamp fixture is suspended over a litter over which the baby chicks or pigs run. A number of the lamps are carried by the fixture, in the present showing four of these lamps, and particular care has to be exercised to prevent overheating of the litter by the rays of the lamp, but most especially to prevent danger of fire should the fixture for any cause whatsoever drop onto the litter while the lamps are hot, or the current is still flowing through the lamps.

The inventive concept includes in such a fixture means for cutting off the flow of current to all of the lamps carried by the fixture in the event that the lamp fixture drops under any cause.

The infrared lamps have to be exposed, particularly over their outer surfaces, so that the rays may travel therefrom to the litter to radiate the heat in the pattern desired.

The fixture herein shown is quite similar to that shown in the co-pending application serial No. 244,234, which issued on July 15, 1952 as Patent No. 2,603,738 wherein three of the co-inventors named in this application are the inventors named in the co-pending application.

The inventive concept further embodies a very simple structure wherein the fixture is required to be tilted onto its side when it falls to break the circuit through the lamps, so that the lamps in any event do not come down onto the litter with their greatest area in contact therewith.

These and other objects and advantages of the invention will become apparent to those versed in the art in the following description of one particular form, in which, referring to the accompanying drawings,

Fig. 1 is a view in side elevation and partial section of a structure embodying the invention; Fig. 2 is a wiring diagram; and

Fig. 3 is a bottom plan view; and

Fig. 4 is a view in bottom plan of the cover with the lamp mounting base removed.

A cover 10, generally of disk and planar shape with a downturned rounded flange 11, is provided, and to the underside of this cover 10 there is secured a lamp mounting base 12. This lamp mounting base 12 is of sheet metal, and in convex shape as viewed from the underside.

In the present showing, four infrared lamps 13 are carried by the base 12 through sockets 14. By reason of these sockets 14 being mounted on the convex base 12, the axes of the lamps 13

13 are directed outwardly one from the other, substantially coinciding with the radii of curvature of the base plate 12.

As indicated in Fig. 3, the lamps 13 are equally spaced apart around the base 12.

The base 12 is brought into contact with the underside of the cover 10 by means of an outer flange 15. The flange 15 is secured to the cover 10 by any suitable manner, herein shown as by means of the hook bolts 16 which in turn have a suspending chain 17 engaged therewith, there being three of these hooks, and three branches 18, 19, and 21, extending from the chain 17 to engage with these hook bolts 16.

On the top side of the cover 10, where immediate access thereto may be had, there is mounted a thermostat element 22 which, through expansion and contraction in response to temperature changes, operates a switch 23. This switch 23, in the form herein shown, operates to cut in and cut out two of the lamps 13, while the other two lamps remain in the circuit normally, the total output of the heat from these lamps being regulated in that manner.

Within the space 24 between the base 12 and the cover 10 there is mounted a mercury switch 25, removably carried therein by means of the lower and upper spring clips 26 and 27, respectively. These clips 26 and 27 are carried by a bracket 28 in turn mounted on the underside of the cover 10, substantially centrally located in respect to the cover 10. The mercury switch 25 is of that type which when in its vertical position, as indicated in Figs. 1 and 4, is normally in closed circuit condition. When the switch 25 is tilted to one side, that circuit is interrupted by the flow of mercury within the switch. Since this particular type of switch is commercially obtainable, the details thereof are not herein illustrated or described. As indicated in Fig. 2, this switch 25 is placed in the circuit so that when it is open all of the lamps 13 will be de-energized, regardless of the condition of the switch 23 even though it be closed.

A rod 30 is mounted on the base 12 to extend centrally therefrom and vertically downwardly as indicated in Fig. 1. This rod 30 has a length sufficient to cause the cover 10 to rock over on its side or rather onto the flange 11, should the chain 17 break or accidentally become disconnected from its hanger (not shown) to allow the entire fixture to drop. Otherwise the fixture could drop so that it would be supported in that manner by the floor lamps 13 to have the cover 10 substantially horizontally disposed,

in which case all the lamps 13 would be in contact with the litter.

However, by reason of the presence of the rod 30, the cover 10 has to rock to one side of the horizontal, and regardless of which direction it may fall the switch 25 will open and thus cut off the current to all of the lamps 13 so that even though the outermost rims of the lamps 13, not over two of them in any event, come into contact with the litter the lamps will cool off before the litter has been brought up to the temperature of ignition. While the diameter of the rod 30 may be quite small, its length should be preferably at least equal to the length of the diameter of the cover 10. The overall length in any event, would have to be limited by the initial, minimum spacing desired between the lamps 13 and the litter, this spacing generally being on the order of from two feet to two and one half feet, and after a certain initial number of days of brooding, then the cover 10 and the lamps 13 may be gradually spaced an increasing distance from the litter.

Therefore it is to be seen that we have provided an extremely novel, and yet most efficient device, for the purpose intended, and while we have herein shown and described the invention in the one particular form, it is obvious that structural changes may be employed without departing from the spirit of the invention, and we therefore do not desire to be limited to that precise form beyond the limitations which may be imposed by the following claims.

We claim:

1. A brooder heater device for suspension above the floor, comprising a heater unit; a member for carrying the unit; an electric circuit including said unit; a rod carried by said member to extend downwardly therefrom; and a switch in said circuit carried by said member, said switch being characterized by being in closed circuit condition when said device is in its suspended position and automatically going to an open circuit condition in a tilted position of the device as may be induced by said rod contacting the floor upon release of the device from its suspended position.

2. A brooder heater device for suspension above the floor, comprising a heater unit; a member for carrying the unit; an electric circuit including said unit; a rod carried by said member to extend downwardly therefrom; and a switch in said circuit carried by said member, said switch being characterized by being in closed circuit condition when said device is in its suspended position and automatically going to an open circuit condition in a tilted position of the device as may be induced by said rod contacting the floor upon release of the device from its suspended position; said member including a base; said heating unit comprising a plurality of heat lamps mounted in circumferentially spaced relation around said base and directed downwardly; said rod being secured centrally of said lamps to said base; and the diameter of said cover exceeding the diameter of a circle including the outermost portions of said lamps,

the length of said rod being at least equal to the diameter of said cover.

3. A brooder heater device for suspension above the floor, comprising a heater unit; a member for carrying the unit; an electric circuit including said unit; a rod carried by said member to extend downwardly therefrom; and a switch in said circuit carried by said member, said switch being characterized by being in closed circuit condition when said device is in its suspended position and automatically going to an open circuit condition in a tilted position of the device as may be induced by said rod contacting the floor upon release of the device from its suspended position; said switch consisting of a mercury tube switch mounted on said member to have its axis vertically disposed in said cover suspended position, whereby said switch is operable to its open circuit condition in all directions of tilting of the cover.

4. A brooder heater device normally suspensable in spaced relation above the floor comprising a heater unit; a member carrying the unit; an electric circuit including said unit; a tilting element carried by said member to project from its underside to cause the member when free to tilt to one side when said element rests on the floor; and a switch in said circuit and carried by said member, said switch being characterized by being normally in closed circuit condition when said member is suspended and going to open condition upon the tilting of said member.
